US00D495604S1

(12) **United States Design Patent** (10) Patent No.: **US D495,604 S**
(45) Date of Patent: **** Sep. 7, 2004**

(54) **BOTTLE**

(75) Inventors: **Douglas M. Lund**, Hillsborough, NJ (US); **Wendy Slavish**, Collegeville, PA (US); **Erik Boissonneault**, Reading, PA (US)

(73) Assignee: **Johnson & Johnson Consumer Companies, Inc.**, Skillman, NJ (US)

(**) Term: **14 Years**

(21) Appl. No.: **29/168,097**

(22) Filed: **Sep. 26, 2002**

(51) LOC (7) Cl. **09-01**

(52) U.S. Cl. **D9/542; D9/550; D9/558**

(58) Field of Search D9/516, 530, 539, D9/550, 563, 558, 549, 571, 572, 573, 574; 215/12.2, 384; 220/660, 669; 222/321.1, 321.7, 321.9, 206, 212, 213, 215; 239/333

FOREIGN PATENT DOCUMENTS

AU 90465 S 6/1985

(List continued on next page.)

Primary Examiner—Carol Rademaker

CLAIM

The ornamental design for a bottle, as shown and described.

DESCRIPTION

FIG. 1 is a perspective view of the bottle of our new design as seen from the top, front, and right sides;

FIG. 2 is a front elevational view thereof, the rear elevation being a mirror image, except for the unclaimed threads;

FIG. 3 is a left side elevational view thereof, the right side elevation being a mirror image, except for the unclaimed threads; and,

FIG. 4 is a top plan view thereof.

The broken lines shown in the drawings are for illustrative purposes only and form no part of the claimed design.

1 Claim, 4 Drawing Sheets
